B. W. KENDALL

ELECTRICAL RECEIVING OR REPEATING APPARATUS

Original Filed Feb. 20. 1917

Inventor:
Burton W. Kendall.
by W. Beatty Atty.

UNITED STATES PATENT OFFICE.

BURTON W. KENDALL, OF NEW YORK, N. Y., ASSIGNOR TO WESTERN ELECTRIC COMPANY, INCORPORATED, OF NEW YORK, N. Y., A CORPORATION OF NEW YORK.

ELECTRICAL RECEIVING OR REPEATING APPARATUS.

Original application filed February 20, 1917, Serial No. 149,782. Divided and this application filed January 16, 1920, Serial No. 351,873. Renewed June 4, 1923.

To all whom it may concern:

Be it known that I, BURTON W. KENDALL, a citizen of the United States, residing at New York, in the county of New York, State of New York, have invented certain new and useful Improvements in Electrical Receiving or Repeating Apparatus, of which the following is a full, clear, concise, and exact description.

10 This invention relates to electrical receiving or repeating apparatus, and constitutes a division of my application Serial No. 149,782 filed Feb. 20, 1917 issued as Patent No. 1,453,982, on May 1, 1923.

15 A particular application of the invention is to receiving apparatus or repeaters for submarine cables or similar conductors, in connection with which it will be described. Its object is, in this case, to amplify and

20 repeat messages from an incoming cable to an outgoing cable while permitting duplex operation of said cables. A further object is to receive and amplify signals with fidelity so that the recorded signals shall be 25 enlarged and faithful copies of the signal wave-forms.

These objects are accomplished by inserting 30 a transformer winding in the circuit from which signals are to be received, connecting another winding of the transformer to an amplifier which has in its output circuit an electrical network of special form, to be more particularly described later, amplifying the power appearing in one branch 35 of this network, and transferring it to an instrument or circuit in which it is to be utilized. The advantages secured by this invention and the difficulties which are overcome will be better understood after a 40 brief explanation of the operation of duplex cables, reference being made to the drawings.

Referring to the drawing, the reference numerals 4 and 5 represent two cables, and it is desired to send signals from the station 45 7 to the station 8, making use of a relay between the terminals of the cables 4 and 5 in such a manner as to permit of duplex operation. At the terminals of the cable 50 4 there are two artificial cables 10 and 11 arranged to have characteristics similar respectively to those of the actual cable. At the station 7 there are connected, between

the cable 4 and the artificial cable 10, the two condensers 12 and 13, across which is 55 bridged in the usual manner some indicating instrument 14. The opposite terminal of the cable 4 likewise has the usual condensers 16 and 17, across which would ordinarily be connected some indicating instrument in the same manner as at the station 7. When a signal is sent from the station 7 by the operation of the key 18 in series with the grounded battery 19, an impulse is sent over the cable 4 and the artificial 60 cable 10, and the circuit is so balanced that there is no potential difference between the points 21 and 22. A potential difference is, however, created between the points 24 and 25 at the further end of the cable 14, 70 and this potential difference would, in general, be used to operate an indicating instrument in a manner which is well-known in connection with such duplex operation.

An impulse impressed across the points 75 28, 29 and coming from any source such as a battery with a key or from the output circuit of a relay, as indicated in this figure, will produce a current which divides 80 equally between the paths 4 and 11 of equal impedance, and because of this symmetry, there is for such a signal or impulse no difference of potential between the points 24 and 25, across which a receiving instrument might be connected. Such a receiving 85 instrument will, therefore, not be influenced by signals impressed between the points 28 and 29. The arrangement of cable 5 with its artificial cables is the same as that of cable 4 with its artificial cables. If now it 90 is desired to relay a message from cable 4 to cable 5, it will be necessary to connect, through an amplifier, the receiving terminals 24, 25 of the first cable with the transmitting terminals 30, 31 of the second cable, 95 and similarly to connect the receiving terminals 33, 34 with the transmitting terminals 28, 29.

It has been found that an ordinary relay or mechanical amplifier is not suitable for 100 this class of work but that a thermionic amplifier of the audion type may be made to operate very efficiently. Such amplifiers have been used extensively in telephony, and are now well-known in the art. This type 105 of amplifier consists of an evacuated vessel

in which are contained three electrodes, a hot electron-emitting cathode, a cool anode and an auxiliary electrode usually located between the anode and the cathode. The 5 auxiliary electrode and the cathode, constituting the input terminals of the amplifier, are connected to the circuit the power of which is to be amplified, and the cathode and the cool electrode or plate, constituting 10 the output terminals are connected to the circuit in which the amplified power is to appear.

When a voltage is impressed upon the input circuit of such an amplifier, its effect 15 is to vary the strength of the thermionic current which flows between the hot cathode and the cool anode or plate, and since the variations of this current, whose source is a battery in the output circuit, represent 20 larger amounts of power than those required to produce the variations, the device acts as an amplifier. Furthermore, the current in the output circuit of such an amplifier depends only upon the voltage impressed 25 upon its input terminals, the input circuit itself having a very high impedance, and, therefore, taking practically no current and acting as an open circuit. Any variations in the input voltage will be faithfully rendered 30 as corresponding variations in the output current.

Any desired number of amplifiers may be employed for amplifying the signals coming from either line. In the drawing two 35 amplifiers 35 and 40 are shown for amplifying signals to be repeated from 4 to line 5. Two similar amplifiers are shown for repeating in the opposite direction.

An important feature of a thermionic 40 amplifier is that its input and output circuits have one point in common namely, the connection to the hot cathode, so that there is an electrical connection between the two circuits. In using the amplifier as described 45 in connection with the problem of repeating cable messages, there will, therefore, be an electrical connection between the receiving terminals of one cable and the transmitting terminals of the other into which the signals 50 are to be relayed. Examination of the drawing will show that when such a connection exists, that is, when the input terminals of a thermionic amplifier are connected directly to the receiving terminals 24, 25 or 55 33, 34, the artificial lines will be shunted, and their usefulness, therefore, destroyed. In this case duplex operation can not be maintained.

One method of eliminating the circuit 60 connection just noted would be to connect one winding of a transformer across each pair of receiving terminals, one of these transformers being shown as 36 in the drawing, and to connect the other winding to the 65 input terminals of the amplifier. The out-

put terminals of the amplifier would then be connected to the transmitting terminals such as 30, 31 of the other cable.

The simple method, however, is open to a serious objection, for the voltage induced 70 in the secondary of the transformer with essentially an open circuited secondary such as is obtained when connected to the input of a vacuum tube is not proportional to the current in the primary but is proportional 75 to the rate at which this current changes, for example, a voltage is present in the secondary only when the current in the primary is actually changing. It will, therefore, be clear that the repeated current will 80 not be a faithful copy of that of the incoming signal. To overcome this difficulty, that is, to make the voltage over the input terminals of amplifier 40 a copy of the current to be repeated, is the object of the correcting 85 network comprising resistance 37 and condenser 38 whose design and operation are now to be described.

As mentioned above, the electromotive force induced in the secondary of the transformer 36 is proportional to the rate at 90 which the primary current changes, that is, it is proportional to the time derivative of the primary current, and the transformer may, therefore, be spoken of as a differentiating device. In this invention advantage is taken of the fact that a condenser 95 acts as an integrating device, for the potential difference across the terminals of a condenser placed in such a circuit, as shown 100 is proportional to the total quantity of electricity which has passed therethrough, and is, therefore, proportional to the time integral of the current flowing in such a circuit. If the condenser 38 were short-circuited, the current through the resistance 37, there being then in circuit only the internal resistance of the output circuit of the tube 35 and the resistance 38, would be 110 entirely similar to and in phase with the voltage generated in the output circuit of the tube 35. This voltage would be equal to the voltage impressed on the first circuit of the tube multiplied by the amplification 115 factor which expresses the ratio of voltage generated on the output circuit to the voltage impressed on the input circuit. The input voltage, since the transformer 36 has essentially an open circuited secondary, would be proportional to the derivative of 120 the current flowing in the primary of the transformer, i. e., if i is this current, the voltage is

$$M \frac{di}{dt}$$

125

With the interposition of the condenser 38, its value being such that its impedance to all the frequencies concerned is substantially negligible compared to the sum of 130

resistances 37 and the internal output resistance of the tube 35—the impedance of the condenser 50 being negligible to the same or a greater extent, the current flowing through the condenser will still be sensibly proportional to

$$M \frac{di}{dt}$$

- 10 But as the voltage across the condenser is proportional to the integral of the current flowing through 37 this voltage is then substantially proportional to the current flowing through the input transformer. It only 15 remains, then, to provide a grid leak 44 for the tube 40 of such a value as not appreciably to affect this effect of the condenser 38. It is therefore necessary for the proper 20 operation of the arrangement that the impedance of the condenser 38 to the lowest frequency to be transmitted be at once small compared to the resistance 44 and small compared to the sum of the resistance 37 and the output resistance of tube 35. The 25 resistance 37 may even be omitted in case the internal resistance of tube 35 alone is high compared to the impedance of condenser 38.

30 The output circuit of the amplifier 40 is connected, preferably through a condenser 41, to the transmitting terminals 30, 31 of the cable 5. In order to allow the necessary flow of direct current, a choke coil 42 is connected across the output terminals of the 35 amplifier. The amplifier has an output battery 43 which may be connected up in any suitable position in the output circuit.

In practice the following arrangement and dimensions of elements have been found 40 to be very satisfactory. The transformer 36 is arranged to step up the voltage of the incoming signal, for example, to ten times its original value. Its secondary winding is connected to amplifier 35, the output terminals of which are connected to resistance 37 and condenser 38. To provide for the flow of direct current in the output circuit of amplifier 35, a resistance 49 which should preferably be of several thousand ohms is 45 added, and to restrict the direct current to this circuit a large condenser 50 is connected as shown. It has been found that the use of an amplifier between the cable terminals and the correcting network 37, 38 permits the use of a larger transformer 36 than would otherwise be possible, which 50 feature is of advantage in receiving signals of low frequency. By this is meant that a transformer having a large effective reactance, as is the case when the secondary winding has many turns, is more effective in transmitting low frequency waves than a transformer having smaller inductance. In order to reduce the distortion of the incoming signal to a sufficiently small quan-

tity, the sum of the resistance 37 and the internal output resistance of the tube 35 should be large in comparison with the impedance of the condenser 38, and also the impedance of the condenser 50 should be negligible in this circuit (35—50—37—38). For example, if the output resistance of the tube 35 is 100,000 ohms, and if the lowest signaling frequency is 16 cycles, and the condenser 38 is 1^{mf}, the impedance of the 75 condenser will be about $\frac{1}{10}$ the output impedance of the tube. In this case the resistance 44 may be in the neighborhood of 200,000 ohms.

In addition to the circuit as described, it 80 may be desirable under some conditions to use a resistance 44 bridged across the condenser. This resistance is primarily intended to serve as a leak between the grid and filament of the amplifier 40. This 85 resistance should be an exceedingly high one, say of the order of one or two megohms in order that it shall not act as a substantial short-circuit of the condenser 38 and thereby prevent a building up of the desired 90 voltage in the condenser 38. If this resistance 44 is large it will be apparent that the current flowing therethrough will be proportional to the voltage across the condenser 38, and will therefore, be proportional 95 to the current through primary of the transformer 36.

To secure transmission from cable 5 to cable 4 an exactly similar arrangement of circuits is made to connect the receiving 100 terminals 33, 34 of the cable 5 with the transmitting terminals 28, 29 of the cable 4. By this arrangement it is possible to secure 105 amplification of signals in both directions and also to preserve the property of duplex operation.

It is to be noted that the cathode of the amplifier 40 is connected to ground through the battery 43. This grounding of the cathode of a vacuum tube through a low resistance path has the advantage that in so doing a definite potential may be maintained between each piece of apparatus in the circuit and ground, whereby any local circulation of power, which might lead to the tubes 110 "singing" is substantially avoided. Thus if the cathode 46 of tube 40 were not grounded, the choke coil 42 and the transformer 36, for example, would each have a certain capacity to ground, which would tend to 115 facilitate a transfer of energy from the output circuit back to its input circuit and to start the tube to "singing." Such a feed back, however, is prevented by grounding the cathode, as shown, which is a common 120 terminal for both the input and the output circuits of the tube.

Vacuum tubes 55 and 56 also have their cathodes grounded, so that all the vacuum tube repeaters in the two way repeating sta- 130

tion have grounded cathodes, which condition diminishes considerably, if not entirely eliminating, any cross talk between the two repeating paths. Ordinarily the two circuits containing the vacuum tubes 35, 40 and 55, 56 would be situated close enough together to establish an appreciable capacity effect between apparatus in the two circuits, so that with ungrounded cathodes, a message being sent through one path would induce alternating currents in the other path thereby giving rise to cross talk. This objectionable feature may be substantially eliminated however by the grounding described above.

The function of the condenser 38 and the resistance 37 has been given a physical explanation above. The mathematical verification of this explanation is given in my copending application, Serial No. 149,782, filed February 20, 1917.

What is claimed is:

1. The combination with a signal transmission conductor, of a network for improving the wave form of signals transmitted thereto from said conductor, a vacuum tube repeater between said conductor and said network and a transformer between said repeater and said transmission conductor.
2. A receiving system for signals comprising a line conductor, a correcting network, a vacuum tube between said conductor and said network, said network being composed of ohmic resistance and condensive reactance, and being substantially free from inductive reactance, and a transformer between said tube and said line.
3. A two-way repeating system comprising means for repeating signals in one direction, means for repeating signals in the opposite direction, each of said means comprising an incoming conductor, a correcting network, a vacuum tube repeater between said conductor and said network, said network being composed of ohmic resistance and condensive reactance and being substantially free from inductive reactance, and a transformer between said tube and said incoming conductor.
4. A receiving system comprising an incoming conductor, and means for transmitting the component parts of the signals from said conductor with equal attenuation, said means comprising a differentiating device, an integrating device, and amplifying means located between said devices.

5. A transmission system comprising an incoming line, a transformer, a vacuum tube repeater in circuit therewith, and a waveform correcting device in the output circuit of said repeater, said transformer being located between said line and said repeater.

6. In a transmission system, a transmission device the attenuation of which varies with the frequency, an auxiliary system the

attenuation of which varies with the frequency in a manner complementary to that of said device so that the resultant transmission of said device and said auxiliary system is substantially constant over a wide range of frequencies, and a repeater between said device and said system.

7. The combination with a transmission element in which the attenuation varies with different frequencies of means for impressing on said element waves of a plurality of frequencies, means for amplifying said waves after said unequal attenuation is produced, and an auxiliary system associated with said amplifying means to equalize the attenuation caused by said element so that all frequencies within a wide range are transmitted with practically uniform attenuation, said auxiliary system comprising a network composed of ohmic resistance and condensive reactance and being substantially free from inductive reactance.

8. The combination with a submarine cable, of a network for improving the wave form of signals transmitted thereto from said cable, a vacuum tube amplifier between said cable and said network, and a transformer between said amplifier and said cable.

9. In a transmission system, a transmission element the attenuation of which varies with the frequency, means, the attenuation of which varies with the frequency in a manner substantially complementary to that of said element so that the resultant transmission of said element and said means is substantially constant over a wide range of frequencies, and a vacuum tube amplifier between said element and said means.

10. In combination, two vacuum tubes, each having an anode, a cathode and a control electrode, a connecting line between the anode of one tube and the control electrode of the second tube, comprising a condenser and a resistance serially connected between said anode and said control electrode, a connecting line between said cathodes and a condenser connected across said lines.

11. In a transmission system for the simultaneous transmission of waves of a plurality of frequencies, transmission means in which the different frequencies are attenuated by different amounts, a two stage amplifier for amplifying said waves, and a network between the two stages of said amplifier for attenuating the waves in a sense opposite to the attenuation produced by said transmission means.

12. A transmission system comprising a transmission element the attenuation of which varies with the frequency, an auxiliary system the attenuation of which varies with the frequency in a manner complementary to that of said element so that the resultant transmission of said element and

said auxiliary system is substantially constant over a wide range of frequencies, an electric discharge repeater between said element and said system, an outgoing line, and a second electric discharge repeater between said system and said line.

13. An amplifying and wave form correcting system for distorted submarine cable signals comprising two amplifiers and a network between said amplifiers having resistance and reactance for improving the signal wave form.

14. An amplifying and wave form correcting system for distorted submarine cable signals comprising two space discharge repeaters, each having an anode, a cathode and an impedance control element, and an attenuating network between said repeaters for improving the signal wave form.

15. 15. A repeating and wave form correcting system for distorted signal waves comprising two space discharge repeaters and a

reactive network between said repeaters for improving the signal wave form, said network having appreciable resistance which 25 functions to modify the magnitude of the effect of the reactance upon the wave form.

16. A submarine cable for transmitting telegraphic signals involving only relatively low frequencies and in which attenuation of signals is very great, wave form correcting means associated with said cable and comprising a reactive network having appreciable resistance which functions to modify the magnitude of the effect of the 35 reactance upon the wave form, and a space discharge repeater between said network and said cable, said repeater having an anode, a cathode and an impedance control element.

In witness whereof, I hereunto subscribe 40 my name this 13th day of January, A. D. 1920.

BURTON W. KENDALL.
